BOWLING ALLEY PIN SETTING APPARATUS

Wilbert F. Kling, Detroit, Mich.

Application August 3, 1949, Serial No. 108,292

10 Claims. (Cl. 273—42)

1

The invention concerns a bowling alley and is particularly directed to bowling alleys constructed on a small scale.

The problems encountered in the construction of small-scale bowling alleys are somewhat similar to those encountered in full-scale alleys. However, certain of the problems are magnified because of space limitations. For example, the ball in full-scale alleys is thrown by the player, whereas in a toy-size model this would be a totally inadequate method because of the resulting bouncing and lack of control. Further, even with a suitable provision for propelling the ball, there arises the problem of the severe impact of the ball against the rear wall of the alley.

In a full-scale model there is adequate space for an operator or pin-setter to move about while recovering and setting the pins. In small-scale alleys, on the other hand, it is a problem to provide a mode of preventing the pins from being scattered and at the same time prevent the pins from being deposited in a recessed area from which they cannot readily be recovered.

Likewise, the setting up of a small pin presents an aggravated problem in that the bottom surface area of the pin is quite small. The small surface area leads to a corresponding instability of the pins and resulting difficulty in setting them up. There are available to the art methods of setting pins in full scale alleys but again adaptation of these methods on a small-scale raises the problem of providing an apparatus which can operate efficiently in the limited space available.

It is an object of this invention to provide a bowling alley which includes new and improved facilities for the handling of the bowling pins.

It is also an object of this invention to provide a small scale bowling alley apparatus which is convenient to operate and which provides many of the recreational features of a full-scale alley.

A pin setting apparatus which is a feature of the invention holds the pins directly above their positions on the bowling surface and discharges them at said positions when the apparatus is lowered; the apparatus comprising a top panel provided with a plurality of holes, each hole adapted to receive a pin for passage therethrough; a plurality of cylinders attached to the underside of said top panel and each positioned concentrically to a hole in said top panel and adapted to receive a pin for passage therethrough; a bottom panel provided with a plurality of holes, each hole adapted to receive a pin for passage therethrough, said top and bot-

tom panels forming a pin holding and pin discharging assembly mounted for vertical movement above the bowling surface; said top panel being movable laterally relative to said bottom panel from a first position wherein the respective holes in the panels and the cylinders are in alignment such that a bowling pin will pass completely through said openings to a second position wherein the openings in said bottom panel are out of alignment with the openings in the top panel such that bowling pins enclosed in said cylinders rest on the body of said bottom panel; a lever member pivotally secured to said pin holding assembly for vertical movement therewith; a first lever arm as a portion of said member and pivotally secured to said top panel for lateral movement therewith; a second lever arm as a stop engaging portion of said member; a third lever arm as a portion of said member and extending oppositely to said second lever arm; resilient means connecting said third arm with a portion of said pin holding assembly, said first arm moving laterally in response to vertical movement of said second arm and said resilient means tending to force said second lever arm and consequently said top panel into either of its extreme lateral positions depending on the position of said resilient means relative to the pivot point of said member on said pin holding assembly; a stop positioned near the top of said bowling alley adapted to engage and limit the upward movement of said second lever arm thereby causing said first arm to move laterally and said top panel to move to its closed position upon upward movement of the pin holding assembly; a stop positioned near the bowling level of said alley adapted to engage and limit the downward movement of said second lever arm thereby causing said first arm to move laterally and consequently said top panel to move to its open position upon downward movement of said pin holding assembly; and resilient guide means secured to a portion of said bowling alley and adapted to support said pin setting assembly.

Other objects and features of novelty of the invention will be specifically pointed out or will become apparent when referring, for a better understanding of the invention, to the following description taken in conjunction with the accompanying drawings, wherein:

Figure 1 is a plan view of a bowling alley illustrating one embodiment of the invention;

Fig. 2 is a section along the line 2—2 of Fig. 1;

Fig. 3 is a section along the line 3—3 of Fig. 1;

Fig. 4 is a section along the line 4—4 of Fig. 1.

Fig. 5 is a plan view of a bowling alley illustrating the alternative pin setting apparatus; Fig. 6 is a side view of Fig. 5 partially in section;

Fig. 7 is a rear view of the apparatus of Fig. 5; Fig. 8 is a sectional view of Fig. 5 taken along the line 8-8.

Fig. 9 is a sectional view of Fig. 5 taken along the line 9-9.

Referring more particularly to the drawing:

The bowling alley consists generally of a front wall 10, a rear wall 11, side walls 12, supporting legs 13, a bowling surface 14, and a ball-return track 15.

Positioned forwardly of the front end of the bowling surface is a sighting device 16 which is adapted to hold the ball prior to its being propelled and to direct the ball after motion has been initiated.

The sighting device 16 as shown consists of a crimped sheet having a sighting portion 17 and a support portion 18. The sight 17 itself consists of an upwardly, concave, arcuate channel of the same general curvature as the bowling ball. The support portions 18 of the sighting device 16 are on each side of the sight and are adjusted so that the lowest line of the concave channel surface is in alignment with the bowling surface 14, in a manner such that the ball, in passing from the channel to the bowling surface 14, moves in substantially the same plane.

The sighting device 16 is slidably mounted on a surface 19, the plane of which is slightly lower than the bowling surface 14, in order to accommodate the support portions 18 of the sighting device. A bolt 20 is loosely fastened to the underside of the sighting device 16 and passes through a slot 21 in the surface 19 in a manner permitting both sideways and rotational movement of the sighting device 16. The sighting device 16 is shown in solid lines in one position in Fig. 1 and is shown as a broken line in an alternate position.

An area 22 generally triangular in shape near the rear portion of the bowling surface serves as the site for the bowling pins 23 when they are set in position for play. The pins 23 are each provided with a hole 24 extending upwardly from its bottom surface, said holes 24 being adapted to receive balancing or stabilizing pins 25.

The bowling 14 surface of the bowling pin area 22 is provided with a number of holes 26, each of which is directly under a designated position for a bowling pin 23 and each of which lies concentrically with the hole 24 in the correspondingly positioned pin.

A platform 27 is movably mounted under the bowling surface 14 and directly below the bowling pin area 22. The platform 27 consists of a flat member having attached thereto a number of balancing pins 25, one for each bowling pin 23, each balancing pin 25 being positioned in a manner such that it is directly below the designated position for the corresponding bowling pin 23 and in a manner such that it will pass through the corresponding hole 26 in the bowling surface into the corresponding hole 24 in a bowling pin 23 with an upward movement of the platform 27. The platform 27 is also provided with holes 23 adapted to slide over guides 29 attached to the underside of the bowling surface 14, said guides 29 being adapted to prevent sideways movement of the platform 27 and to maintain alignment of the platform members with their coating mem-

bers on and above the bowling surface 14. A lever 30 is pivoted so that one arm 31 engages the underside of the platform 27 and the other arm 32 extends outside the side wall 12 for convenient manipulation. A movement of the exposed arm 32 causes a movement of the platform 27. It is most advantageous that the lever be mounted so that the lever arm 32 rests against the underside of the ball-return track 15 when the platform 27 is at its lowest position. Both lever arms 31 and 32 are shown in solid lines in their positions when the platform 27 is down, and their positions are shown in broken lines when the platform 27 is up.

The lever 30, in its preferred embodiment, is constructed with a channel-shaped cross section and is mounted in a manner such that the platform engaging arm 31 fits within parallel disposed guides 39 attached to the under side of the platform 27.

A recessed space 33 is positioned immediately off the rear edge and below the level of the bowling surface 14. The bottom 34 of the recessed space 33 is built on an incline in order that bowling pins 23 entering the recessed space 33 be deflected to one side. A receptacle 35 for receiving the struck bowling pins 23 is positioned on the side wall 12 just outside the lower end of the inclined bottom 34 of the recessed space 33. A hole 36 in the side wall 12 permits passage of the bowling pins 23 from the recessed space 33 into the receptacle 35.

A swingable, hinged door 64 adapted to swing upwardly toward a horizontal attitude is attached near the back wall 11 of the alley and directly behind the recessed space 33. The hinged member 64 is covered with felt or other suitable material to provide a resilient surface 37. It is the purpose of the hinged member 64 to absorb substantially all the energy of impact of the moving bowling ball after the ball has passed the bowling pin area 22. The hinged member 64 is sufficiently yieldable to allow the ball to pass through the opening provided by the backward movement of the hinged member.

A chamber 38 is provided immediately behind the hinged member 64 to catch the ball. The chamber 38 is connected to the ball-return track 15 and is situated at an elevation such that a ball contained within the chamber 38 will roll into the ball-return track 15. The latter track 15 is inclined downwardly as it approaches the front end of the alley sufficient to cause the ball to return automatically to the front section of the return track 15.

In the use of the bowling alley apparatus of the invention, as shown in Figs. 1-4 inclusive, a player mounts the bowling ball on the adjustable sight and, after taking aim, propels the ball toward the bowling pins with a flick of the finger or by another suitable method. It is sometimes preferred to put a very slight depression in the sight in order to hold the ball steady while aim is being taken.

When the pins are struck by the ball they are propelled backward into the recessed area where they are deflected toward the bowling pin receptacle on the side wall. Meanwhile the ball strikes against the resilient surface of the swingable door and passes into the rear chamber, a substantial portion of its energy having been absorbed by its impact with the door. From the rear chamber the ball follows the return track to the front end of the alley.

When the setting of pins becomes necessary,

they are removed from the convenient receptacle and set in their designated spots on the bowling surface. During the setting operation the hand operated lever is moved in a manner to raise the platform holding the stabilizing pins. These pins extend above the bowling surface and impart stability to the bowling pins when the latter are set over them. When the pins have been set the lever is released and the platform is lowered. This retracts the stabilizing pins to a position below the bowling surface and play may be resumed.

Figs. 5-9, inclusive, show in detail an alternative pin setting apparatus for use with the invention wherein the pins are conveyed to their positions on the bowling surface by means of an assembly which is adapted to hold the pins directly above their bowling surface positions and is also adapted to release the pins when the assembly is lowered.

The pin holding assembly consists of an upper panel 40, cylinders 41, which are secured to the under side of the top panel 40, and a bottom panel 42. The top panel 40 is provided with the holes 43, one for each bowling pin, each of said holes being concentric with the opening of a cylinder 41 which is secured directly beneath the hole 43. The bottom panel 42 is provided with openings 44, one for each bowling pin.

The bottom panel 42 is supported by the side braces 45. Screws 46, or other guide means positioned in the side braces 45, are mounted for engagement in slots 47 in side wall 12 of the bowling apparatus. The screws or guide means 46 maintain the alignment of the pin holding assembly in its vertical movement. Resilient guides 48 serve to support the side braces and pin holding assembly when the assembly is at its highest elevation and while it is being lowered. Downwardly extending portions 49 of the side braces 45 squeeze between the resilient guides 48 and the side wall 12 when the pin-holding assembly is lowered. In this manner a pressure is obtained against the side braces at all positions of said braces.

Lateral movement of the top panel 40 with respect to the bottom panel 42 is made responsive to vertical movement of the pin holding assembly by means of the lever indicated generally by 50. The lever 50, pivoted at a point 51, consists of a first lever arm 52, a second lever arm 53 and a third lever arm 54. The first lever arm 52 is engaged with a bracket 55 by means of the pin 56, the bracket 55 in turn being secured to the top panel 40 for lateral movement therewith. The third lever arm 54 is connected by means of a tension device such as a spring 57 to a portion 58 of the pin holding assembly.

As shown, particularly in Fig. 9, the pivoting point 51 for the lever 50 consists of a wire 59 or the like which is secured to brackets 60 of the pin holding assembly by the screws 61.

On upward movement of the lever 50 the second lever arm 53 is brought into contact with a stop 62 which, as shown, is the support for the swingable door 64. Contact of the lever arm 53 with the stop 62 causes the lever arm 54 to move upwardly with respect to the lever arm 53 and causes the lever arm 52 to move rearwardly. In this manner there is a lateral movement of the top panel toward the rear of the assembly causing the openings 43 of the top panel to be out of alignment with the openings 44 in the bottom panel. The assembly is held in this position

by the spring 57 which is, as shown, slightly over the pivot point 51 of the lever 50.

When the pin holding assembly and the lever 50 are moved downwardly to the position shown in the dotted lines of Figs. 6 and 8, the lever arm 53 is brought into contact with the stop 63 which limits the downward movement of the lever 50. This causes the lever arm 54 to move downwardly relative to the arm 53 and causes the lever arm 52 to move forward thus causing a forward lateral movement of the top panel with respect to the bottom panel. In this manner the holes 43 in the top panel are brought into alignment with the holes 44 in the bottom panel and the pins held in the pin holding assembly are discharged. When the lever 50 is in the lower position, the spring 57 is slightly below the pivot point 51 thus holding the lever in position until it has been raised to encounter the stop 62.

20 I claim:

1. In a bowling alley, a pin setting apparatus comprising a top panel provided with a plurality of holes, each hole adapted to receive a pin for passage therethrough; a plurality of cylinders attached to the underside of said top panel and each positioned concentrically to a hole in said top panel and adapted to receive a pin for passage therethrough; a bottom panel provided with a plurality of holes, each hole adapted to receive a pin for passage therethrough, wherein said top and bottom panels form a pin holding and pin discharging assembly mounted for vertical movement above the bowling surface and wherein in said top panel is movable laterally relative to said bottom panel from a first position wherein the respective holes in the panels and the cylinders are in alignment such that a bowling pin will pass completely through said openings to a second position wherein the openings in said bottom panel are out of alignment with the openings in the top panel such that bowling pins enclosed in said cylinders rest on the body of said bottom panel; a level member pivotally secured to said pin holding assembly for vertical movement therewith; a first lever arm as a portion of said member and pivotally secured to said top panel for lateral movement therewith; a second lever arm as a stop engaging portion of said member; a third lever arm as a portion of said member and extending oppositely to said second lever arm; resilient means connecting said third arm with a portion of said pin holding assembly, said first arm moving laterally in response to vertical movement of said second arm and said resilient means tending to force said second lever arm and consequently said top panel into either of its extreme lateral positions depending on the position of said resilient means relative to the pivot point of said lever member on said pin holding assembly; a stop positioned near the top of said bowling alley adapted to engage and limit the upward movement of said second lever arm thereby causing said first arm to move laterally and said top panel to move to said second position upon upward movement of the pin holding assembly; a stop positioned near the bowling level of said alley adapted to engage and limit the downward movement of said second lever arm thereby causing said first arm to move laterally and consequently said top panel to move to said first position upon downward movement of said pin holding assembly; and resilient guide means secured to a portion of said bowling alley and adapted to support said pin setting assembly.

2. In a bowling alley in which two oppositely

disposed vertical walls are provided with vertically extending slots; a pin setting apparatus comprising a top panel provided with a plurality of holes, each hole adapted to receive a pin for passage therethrough; a plurality of cylinders attached to the underside of said top panel and each positioned concentrically to a hole in said top panel and adapted to receive a pin for passage therethrough; a bottom panel provided with a plurality of holes, each hole adapted to receive a pin for passage therethrough, wherein said top and bottom panels form a pin holding and pin discharging assembly mounted for vertical movement above the bowling surface and wherein said top panel is movable laterally relative to said bottom panel from a first position wherein the respective holes in the panels and the cylinders are in alignment such that a bowling pin will pass completely through said openings to a second position wherein the openings in said bottom panel are out of alignment with the openings in the top panel such that bowling pins enclosed in said cylinders rest on the body of said bottom panel; a lever member pivotally secured to said pin holding assembly for vertical movement therewith, a first lever arm as a portion of said member and pivotally secured to said top panel for lateral movement therewith; a second lever arm as a stop engaging portion of said member; a third lever arm as a portion of said member and extending oppositely to said second lever arm; resilient means connecting said third arm with a portion of said pin holding assembly, said first arm moving laterally in response to vertical movement of said second arm and said resilient means tending to force said second lever arm and consequently said top panel into either of its extreme lateral positions depending on the position of said resilient means relative to the pivot point of said member on said pin holding assembly; a stop positioned near the top of said bowling alley adapted to engage and limit the upward movement of said second lever arm thereby causing said first arm to move laterally and said top panel to move to said second position upon upward movement of the pin holding assembly; a stop positioned near the bowling level of said alley adapted to engage and limit the downward movement of said second lever arm thereby causing said first arm to move laterally and consequently said top panel to move to said first position upon downward movement of said pin holding assembly; resilient guide means secured to a portion of said bowling alley and adapted to support said pin setting assembly; and oppositely disposed guide members extending outwardly from said pin holding assembly and adapted to ride in said vertically extending slots with vertical movement of said assembly.

3. The combination with a bowling alley having a plane surface, a set of pins for one end of said alley, a pin-setting device on said end of the alley, said pin-setting device including a top and bottom panel movable vertically as a unit and relatively shiftable horizontally, said panels having apertures through which pins may pass when the panels are in one relative horizontal position, with the bottom panel preventing such passage in another horizontal relative position of the panels for supporting the pins in vertical position when placed within the apertures of the top panel, a lever pivoted on the bottom panel and pivotally connected to the top panel, means on said alley for shifting said lever near the end of the upward movement of the panels to produce relative horizontal shifting thereof for retaining the pins

when the panels are in raised position, and means on said alley for shifting the lever in the opposite direction when the panels are lowered for relatively shifting the panels horizontally for setting the pins on the alley surface.

4. The combination with a bowling alley having a plane surface, a set of pins for one end of said alley, a pin-setting device on said end of the alley, said pin-setting device including a top and bottom panel movable vertically as a unit and relatively shiftable horizontally of the alley bed, said panels having apertures through which pins may pass when the panels are in one relative horizontal position, with the bottom panel preventing such passage in another horizontal relative position of the panels for supporting the pins in vertical position when placed within the apertures of the top panel, a lever pivoted on the bottom panel and pivotally connected to the top panel, means on said alley for shifting said lever near the end of the upward movement of the panels to produce relative horizontal shifting thereof for retaining the pins when the panels are in raised position, means on said alley for shifting the lever in the opposite direction when the panels are lowered for relatively shifting the panels horizontally for setting the pins on the alley surface, and spring means effective in both positions of said lever for retaining the panels and lever in shifted position.

5. The combination with a bowling alley having a plane surface, a vertically movable frame at one end of the alley provided with a horizontal area having apertures therein through which individual pins of a set may pass, downwardly extending arms on said frame, channel members on the alley extending upwardly for encompassing said downwardly extending arms for supporting and guiding said frame in vertical position, a shiftable rack on said area having apertures therein which align with the apertures in the area when in one position and which are out of alignment with said apertures in another position, said rack having an extending arm and said frame having a rear portion in which said arm is shiftable, a lever pivoted to said rear portion of the frame having an extending finger which is pivoted to said arm, and means on said alley for interrupting the movement of the lever with the frame as the frame is both raised and lowered to shift the lever from one to another position which shifts the arm and rack into a position in which the apertures are aligned and into another position in which they are out of alignment.

6. The combination with a bowling alley having a plane surface, a vertically movable frame at one end of the alley provided with a horizontal area having apertures therein through which individual pins of a set may pass, downwardly extending arms on said frame, channel members on the alley extending upwardly for encompassing said downwardly extending arms for supporting and guiding said frame in vertical position, a shiftable rack on said area having apertures therein which align with the apertures in the area when in one position and which are out of alignment with said apertures in another position, said rack having an extending arm and said frame having a rear portion in which said arm is shiftable, a lever pivoted to said rear portion of the frame having an extending finger which is pivoted to said arm, means on said alley for interrupting the movement of the lever with the frame as the frame is both raised and lowered to shift the lever from one to another position which shifts the arm and rack into a position in which

the apertures are aligned and into another position in which they are out of alignment, and spring means interconnected between the rear portion of the frame and said lever retaining the lever and rack in either of the shifted positions.

7. The combination with a bowling alley having a plane surface, a vertically movable frame at one end of the alley provided with a horizontal area having apertures therein through which individual pins of a set may pass, downwardly extending arms on said frame, channel members on the alley extending upwardly for encompassing said downwardly extending arms for supporting and guiding said frame in vertical position, a shiftable rack on said area having apertures therein which align with the apertures in the area when in one position and which are out of alignment with said apertures in another position, said rack having an extending arm and said frame having a rear portion in which said arm is shiftable, a lever pivoted to said rear portion of the frame having an extending finger which is pivoted to said arm, means on said alley for interrupting the movement of the lever with the frame as the frame is both raised and lowered to shift the lever from one to another position which shifts the arm and rack into a position in which the apertures are aligned and into another position in which they are out of alignment, and spring means projecting within said channel means in position to engage the ends of the arm when the frame is in raised position for retaining it in said position.

8. The combination with a bowling alley having a horizontal area containing apertures and side walls near the pin end of the alley containing aligned inwardly directed channels, a frame having a horizontal portion and downwardly extending aligned arms on opposite sides which are received by and guided within said channels for vertical movement, a shiftable rack on said horizontal area having apertures disposed in aligned relation to the apertures through said area in one position and in out-of-aligned relation therewith when shifted, and means engaging at least one of the arms when the frame is in raised position for retaining it in raised position.

9. The combination with a bowling alley having a horizontal area containing apertures and side walls near the pin end of the alley containing aligned inwardly directed channels, a frame having a horizontal portion and downwardly extending aligned arms on opposite sides which are received by and guided within said channels for vertical movement, a shiftable rack on said horizontal area having apertures disposed in aligned relation to the apertures through said area in one position and in out-of-aligned

relation therewith when shifted, means engaging at least one of the arms when the frame is in raised position for retaining it in raised position, a lever carried by said frame for pivotal movement relative thereto, a finger extending from said lever pivoted to said rack for causing the rack to shift from aperture-aligned position to aperture-unaligned position at the lower and raised positions of the frame respectively, and means engaging the lever near the end of the upward and downward movement of the frame for shifting said rack.

10. The combination with a bowling alley having a horizontal area containing apertures and side walls near the pin end of the alley containing aligned inwardly directed channels, a frame having a horizontal portion and downwardly extending aligned arms on opposite sides which are received by and guided within said channels for vertical movement, a shiftable rack on said horizontal area having apertures disposed in aligned relation to the apertures through said area in one position and in out-of-aligned relation therewith when shifted, means engaging at least one of the arms when the frame is in raised position for retaining it in raised position, a lever carried by said frame for pivotal movement relative thereto, a finger extending from said lever pivoted to said rack for causing the rack to shift from aperture-aligned position to aperture-unaligned position at the lower and raised positions of the frame respectively, and means engaging the lever near the end of the upward and downward movement of the frame for shifting said rack, and spring means secured between said lever and frame for retaining the rack in either of its shifted positions.
